UNITED STATES PATENT OFFICE.

HENRY GEISENHÖNER, OF SCHENECTADY, NEW YORK, ASSIGNOR TO THE GENERAL ELECTRIC COMPANY, OF NEW YORK.

SPACE-BLOCK FOR LAMINATED ARMATURES.

SPECIFICATION forming part of Letters Patent No. 631,786, dated August 29, 1899.

Application filed December 15, 1898. Serial No. 699,344. (No model.)

To all whom it may concern:

Be it known that I, HENRY GEISENHÖNER, a citizen of the United States, residing at Schenectady, in the county of Schenectady, 5 State of New York, have invented certain new and useful Improvements in Space-Blocks, (Case No. 983,) of which the following is a specification.

My present invention relates to the ventilating space-blocks now used in the armatures of all dynamo-electric machines, and has for its object to provide a cheap construction by which they may be readily made from magnetic material with considerable saving in cost and the consequent advantage derived from the use of iron. In general these devices have heretofore been made from cast-brass and have been riveted to one of the armature laminations, the usual course 15 being to build up a certain section of the armature of the iron plates and then insert one of the armature laminæ having the space-blocks attached, and so on until a sufficient core has been built. While this is efficient 20 and useful, it is desirable that all of the material in the core of the armature should be of iron so far as it is possible. Other forms of ventilating devices have been devised in which projections upon one of the armature 25 laminations have been formed to hold the other laminæ apart, but the material of which these laminations are formed is quite thin, and this device has not proved effective. By my invention I apply to the lamination 30 ribs or separators of iron, which are held in place by clips punched out from the armature lamination, the office of which is only to retain the ribs or separators in place. Thus no increase of thickness is necessary, only 35 standard laminations being employed. Certain interlocking devices are used by which the ribs are securely held in position.

The device will be better understood from the accompanying drawings, which show an 40 embodiment of the invention.

In the drawings, Figure 1 is a side view of part of an armature lamination equipped with the invention. Fig. 2 is a side elevation of a position of the armature. Fig. 3 is an elevation, partly in section, looking to the left

from the line 3 3 of Fig. 1. Fig. 4 is a perspective of one of the separators. Figs. 5 and 6 are modifications.

In Fig. 1, A is one of the laminations of the armature, having the teeth B B. To this 55 are attached the separators C, each of which consists of a strip of soft iron, such as is shown in Fig. 4. It is provided with loops C' C², punched out from the iron of the strip, and in this case shown as on opposite sides 60 thereof. Other loops A' are punched out from the iron of the lamination A. The parts are assembled by passing the loop C² through one of the loops A' and the loop C' through the other one upon the opposite side of the strip 65 C. The loops A' are then punched into the holes in the loops C' C², securely binding the parts together.

In the modified form shown in Fig. 5 the loops C' C² are cut from a strip the width of 70 which is shown in dotted lines, and then they are bent in opposite directions, so as to support the strip C firmly.

In the further modification shown in Fig. 6 both of the loops C' C² are upon the same 75 side of the strip C. In this case of course the clips or loops A' in the laminations should be so disposed as to preserve the alinement of the strip with the teeth B B; but this is manifest to a skilled mechanic. 80

Other modifications of the invention may be easily devised, which I have not deemed it necessary to illustrate or describe. The preferred form is that illustrated in Fig. 1, and I have found this to be cheap and efficient. 85

What I claim as new, and desire to secure by Letters Patent of the United States, is—

1. The combination with a lamination in a dynamo-electric machine, of ribs secured to 90 the lamination by means integral with the ribs and lamination.

2. A space-block for a dynamo-electric machine secured to one of the laminæ thereof by loops punched from the metal of the space-block and from the lamination. 95

3. The combination of the armature lamination with the ribs projecting from it, and interlocking means between the rib and the armature lamination. 100

4. The combination of a lamination having teeth, with a rib or ribs supporting the metal of the teeth, loops punched from the metal of the lamination, and registering loops 5 punched from the metal of the rib.

5. The combination of the lamination A, with the ribs C, each provided with loops C', C² upon opposite sides thereof, and register-

ing loops A', A² punched from the metal of the laminae.

In testimony whereof I have hereunto set my hand this 13th day of December, 1898.

HENRY GEISENIIÖNER.
